Alexander Dine

UNITED STATES PATENT OFFICE.

STANISLAW PRZEPIORKA, OF MEDINA, NEW YORK.

DESIGN FOR A COMBINED PISTOL AND SABER.

50,629.

Specification for Design.

Patented Apr. 17, 1917.

Application filed December 16, 1916. Serial No. 137,332. Term of patent 7 years.

To all whom it may concern:

Be it known that I, STANISLAW PRZEPIORKA, a subject of the Emperor of Austria, residing at Medina, in the county of Orleans and State of New York, have invented a new, original, and ornamental Design for a Combined Pistol and Saber, of which the following is a specification, reference being had to the accompanying drawing, forming part thereof.

Fig. 2 is a similar view shown in fragmentary portion.

I claim:—

The ornamental design for a combined pistol and saber, as shown.

STANISLAW PRZEPIORKA.
